UNITED STATES PATENT OFFICE.

BERNHARD H. WITTE, OF CHICAGO, ILLINOIS.

SWING.

1,391,153.

Specification of Letters Patent. Patented Sept. 20, 1921.

Application filed April 12, 1919. Serial No. 289,505.

To all whom it may concern:

Be it known that I, BERNHARD H. WITTE, a citizen of the United States, and a resident of the city of Chicago, county of Cook, 5 and State of Illinois, have invented certain new and useful Improvements in Swings, of which the following is a specification.

My invention relates to an improved form of swing mounted on a support, and has for 10 its object the provision, in combination with a swing, of an out-door sleeping compartment. Another object is the provision in a swing mounted on a support, of a pedal for swinging said swing. Another object is the 15 provision in a swing of this character of means for securely locking the swing in a stationary position.

Other objects will appear hereinafter.

The invention consists in the combinations and arrangements of parts hereinafter described and claimed.

The invention will be best understood by reference to the accompanying drawings forming a part of this specification, and in 25 which,

Figure 1, is a perspective view of a swing embodying the invention;

Fig. 2, is a perspective view of a swing embodying the invention, arranged for a 30 sleeping compartment;

Fig. 3, is a fragmental view of Fig. 2, with parts removed;

Fig. 4, is a vertical sectional view taken 35 on line 4-4 of Fig. 1;

Fig. 5, is a vertical sectional view taken on line 5-5 of Fig. 2;

Fig. 6, is a vertical sectional view taken on line 6-6 of Fig. 4, and

Fig. 7, is a top plan sectional view taken 40 on line 7-7 of Fig. 4.

The invention consists principally of a swing, modeled after the usual lawn swing, inclosed completely by screens. The device is mounted in the usual frame 8 from a 45 cross-piece 9. Projecting downwardly from the cross-piece 9 are bolts 10, which are curved to form an open hook at their lower end. Mounted on said hooks of the bolts 10 are downwardly projecting members 11, 50 which are securely fastened by bolts or other suitable fastening means to the body of the swing. The swing itself, the parts of which are preferably construed of wood except where otherwise designated, consists of a 55 floor, embodying boards 12 which are securely fastened to the joists 13 and 14 by any suitable means. Secured to the outer

joists, that is, to the joists 14, are members 15 which project upwardly and are inclined outwardly from the floor of the swing. 60 These members 15 are rigidly secured to the joists 14 at their lower end by any suitable fastening means, preferably bolts. Rigidly secured to the upper end of the members 15 and inclined inwardly therefrom to form 65 the framework of the roof of the swing, are members 16. These members 16 are securely connected at their upper end by a suitable cross-piece 16' to which the same are securely bolted. Securely fastened to 70 the members 16, along the upper edge, are members 17.

Projecting upwardly from the floor and securely fastened at their lower ends to the joists 14 are upright members 18, which 75 form the posts for a door. Members 18 are securely fastened at their upper end, by bolts or other suitable fastening means, to the members 16 and are connected together by means of a transverse member 19, which is also securely connected to the boards 17 and the downwardly projecting member 11. Projecting upwardly from the joists 14, and securely connected thereto, are upright members 20, 80 which serve to support cross-pieces 21 and 21' secured at one end to the upper end of members 20 and at the opposite end to the members 15 by bolts, or other suitable fastening means. 85

Extending transversely of the members 21 and secured thereto are boards 20', which 90 serve to form a seat in the swing. Extending transversely of the members 15 and secured thereto, upwardly of the members 20', 95 are cross-pieces or boards 22 which serve to form the back of the seat. Members 13' are secured to the joists 13 and extend parallel to the members 15 and serve to brace the back of the seat, the boards 22 being securely fastened thereto. The upper member 22', which forms a part of the back of the seat, is positioned so as to be flush with the upper edge of the member 16. Securely fastened to the member 22' and the member 16 100 is a member 22'', which serves to form the top edge of the back of the seat and extends transversely of the swing the full length of the side, said member 22'' being positioned substantially at right angles to the members 22. 110

Secured to the members 15 at one end, and to the members 18 at the opposite end, by bolts or other suitable fastening means, are

members 23 which serve as arms for said seat. Secured to the arms 23, at one side of and extending across the swing, is a member 24 which serves as a support for a table 5 25 which is pivotally connected at 25' to the said member 24. At one side of the swing there is positioned, inwardly of and adjacent the members 15, members 26, which are parallel to the members 15 and which are 10 loosely connected at their upper end to the members 15. These members 26 are pivotally connected to the seat arms 21' and extend below said arms to a point 28. Members 27 are securely fastened at their lower 15 ends to the joists 13, and are secured at their upper end to the exterior end of the elements 21', by means of the same bolt by which the elements 27 are secured. Secured to these members 26 are the members 30, 20 which form the back of the seat at that side of the swing and correspond to the members 22 at the opposite side of the swing. It is thus seen that no rigid connection is made between the members 15 and 25 16 and the side of the swing on which the boards 26 and 27 are formed.

Secured to the members 26 are bolts, which have co-operating thumb nuts 29 thereon. These thumb nuts have outwardly extending lugs, the purpose being to position one of these outwardly extending lugs over the inside of the member 15, thereby holding the side which is constituted by the members 26 and 27 and the boards 30 in its upper 30 right position. Secured to the members 26 are pivotally mounted straps 32, which in turn are pivotally mounted to the screen element 31, this screen element forming a closure for the side on which the elements 35 40 26 and 27 appear. It is thus seen that at this side of the swing the elements 15 are rigidly connected at their lower and upper ends, respectively, to the joists 14 and the members 16. Constructed inwardly and independent of these members 15 are the members 26, which carry the screen element 31 and the seat elements 30, the members 26 being pivoted to the outward end of the seat arms 21'. By loosening the lug of the thumb 45 50 nut 29 from engagement with the member 15, it is seen that the upper end of the members 26, carrying with them the screen element 31, are allowed to assume a horizontal position, the elements 30 thereby lying in the same horizontal plane as the seat elements 20' and forming practically a continuation of the seat on this side of the swing. It is evident that upon the downward swinging of the upper end of this side, the 55 60 lower end of the members 26 will come into engagement with the under side of the members 20' and serve to prevent any further swinging of these members. Upon the downward swinging of the screen element 65 31, attached to the elements 26 as already

described, the screen element will come into contact, at its lower ends, with the members 15 and thereby be forced outwardly from said members 15. To allow this element 31 to move outwardly in this manner, the elements 32 are provided with their pivotal connection, as already described.

Secured to the upper end of the members 15, on the corresponding side, and secured to the upper end of the members 26 is a chain 36 which serves as a reinforcing member to prevent farther downward movement of the outer ends of the members 26, as clearly seen in Fig. 5. On the side of the swing on which the elements 26 are positioned, is also positioned a board 29', similarly constructed and similarly positioned as the member 22'. It will be noted that the board 29' serves as a stop for the members 26 in their upward movement, thereby preventing members 26 from moving inwardly to a position in which they would not lie parallel with the members 15.

As shown in the various figures, the entire swing is screened in, and when one side is lowered as shown in Figs. 2 and 5, the screen element 31 moves to assume a horizontal position. Mounted on a hinge 34 is a screen element 33, which is adapted to be folded upon the roof of the swing when 95 said element 33 is in inoperative position. When the swing is folded into the position shown in Figs. 2 and 5, the member 33 is adapted to be swung downwardly, thereby contacting with the outer end of the member 31 and screening the opening on that side. Additional screen elements 35 are adapted to be inserted in the triangular openings which are formed when the swing is in the position shown in Figs. 2 and 5.

Secured to one of the members 18, at each side of the swing, is a screen door 37. On the side of the swing opposite the member 24 and pivotally secured to the seat arms 23 and 23', are elements 38 which serve, 110 when moved to their horizontal position, as a support for the adjacent end of the table 25. As shown, the elements 38 have, at the ends which engage with the table 25, notches provided therein, which serve to lock the table from lateral movement. The table being hinged at its opposite ends, by raising the end of the table which engages with the elements 38, it may be moved in either direction, thereby affording entrance to the 120 swing, as will be readily understood.

Secured to the floor of the swing, by means of a suitable staple 39 and a hook 40, at one end, is a pedal board 41. At the opposite end of said pedal board is secured a lug 42, 125 through which projects a bolt 44 projecting through the lower end of one of the doors 37. Loosely mounted on the outer end of the bolt 44 is a collar 45, having a lug to which is securely fastened a chain 46, the 130

upper end of said chain 46 being securely fastened to a member 47 which extends diagonally of the support 8 and is securely fastened thereto.

5 Securely mounted in the door through which the member 44 projects, are upright members 48 having a groove, in which is slidably mounted a board 49. As shown in Fig. 6, the element 41 inclines upwardly 10 from its stationary end to where the member 44 projects through the swing. By pedaling the member 41, a swinging motion is imparted to the swing. Upon this pedaling motion of the member 41, the member 44 15 will move vertically upwardly and downwardly, with some lateral motion. Consequently, the provision of an opening through which the member 44 is free to act is necessary, and to close this opening when the 20 member 41 is not being pedaled, the member 49 is provided. As is evident, the member 49 is constantly in contact with the member 44, moving vertically up and down as the member 41 is being pedaled.

25 Projecting laterally from and connected with the bolt 44 is a rod 50', which is pivotally connected, at its opposite end, to the member 13', the purpose of the member 50' being simply to steady the member 41 as it 30 is being operated.

Projecting upwardly from the joists 13 and rigidly connected thereto at one end are members 54', which are connected at their upper end to the cross-pieces of the seat corresponding to the cross-pieces 21 and 21'. Pivotally connected to one of these members, by suitable fastening means, are levers 51.

35 A U-shaped member 50 is positioned in said swing, having the base of the U positioned beneath the floor of the swing, the legs of said U-shaped member extending parallel to and in engagement with the oppositely positioned members 54'. Secured to the upper ends of the upwardly projecting 40 legs of the U-shaped member are angle irons 53, having one web in close engagement with the members 54', the web which is in engagement with the member 54' having an elongated slot provided therein with which co- 45 operates a bolt or pin 54 projecting through the member 54'. The object of having an angle iron with the slot and the coöperating pin or bolt is to steady the U-shaped member in its downward and upward movements. Intermediate its ends, the lever 51 50 is secured to the legs of the U-shaped member, a plurality of holes being provided in said upwardly extending legs to permit of adjustment. As shown in Fig. 6, a downward movement of the free end of the lever 51 will effect a downward movement of the U-shaped member 50, which will consequently engage with the ground and serve to prevent any swinging motion of the 55 swing. Secured to the side of the swing are

angle irons 54 and 55, angle iron 54 serving as a rest for the free end of the lever 51 when the U-shaped member is in its raised position, and the angle iron 55 serving as a means of locking the free end of the lever in 70 its lowered position, thereby securely locking the U-shaped member in close engagement with the ground. As shown in Fig. 7, the free end of the lever is offset so as to bring said free end approximately flush with 75 the edge of the seat, thereby placing said lever in a position which will be easily reached by one sitting in the seat of said swing. The free end of the lever 51 will permit of sufficient lateral play to allow of its disengagement with the member 54 and likewise with the member 55, so that the U-shaped member is easily and quickly moved from its free to its operative positions, or vice versa, and securely locked in either position. 80

85 In a device such as described, it is apparent that the swing may be used for a variety of purposes, either as a swing solely, or as an out-door sleeping compartment. When the swing is arranged for a sleeping 90 compartment, as shown in Fig. 5, the table 25 is removed from the table support 24 and is positioned upon the edges of the seats of the swing, thereby forming, with the seats of the swing and the back of the downwardly positioned side, a substantially continuous body upon which may be placed a cot or mattress, as may be desired.

95 There is also provided a means for retaining the swing in a stationary position, when the table is being used or when the swing is being used as a sleeping compartment.

100 The means of joining the various parts together also permits of a ready and rapid assembling or disassembling of the entire device.

105 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 110 the appended claims.

115 Having described my invention, what I claim as new and desire to secure by Letters Patent is:—

1. In a convertible frame swing suspended from a support having oppositely disposed seats, the back of one of said seats being pivotally mounted to move to a horizontal position and be retained in such position; a hinged leaf for engaging the outer 120 end of said seat to cover same; and a member extending from one seat to the other to provide a bedding support, substantially as described.

2. In a frame swing mounted on a sup- 130

port, means for swinging said swing; a ground-engaging member on said swing for locking the same against swinging motion; and lever operated means for raising and 5 lowering said ground-engaging member relatively to said swing, substantially as described.

3. In a frame swing mounted on a support, means for swinging said swing; a 10 ground-engaging member for locking said swing against swinging motion; means for raising and lowering said ground-engaging member relatively to said swing; and means for locking said member in its raised or low- 15 ered position, substantially as described.

4. In a convertible screen-covered frame swing suspended from an overhead support, a seat having a pivotally mounted back; a 20 catch normally retaining said pivoted seat back in upright position; said pivoted seat back adapted to be moved to horizontal position when the catch is released; a hinged screen-covered fly leaf normally folded 25 against said frame and adapted to engage the outer end of said horizontal seat to cover same; and a flat member adapted to extend from the edge of one seat to the edge of the other to form a support for bedding, substantially as described.

30 5. In a convertible swing suspended from an overhead support; oppositely disposed seats in said swing; pivoted members on the arms of said seats at one side thereof and having notches at their ends and a supporting member on the arms of said seats at the 35 opposite side thereof; and a table pivotally mounted on said support and adapted to engage the notches in said pivoted members to prevent movement of the swing, substantially as described.

6. In an insect-proof swing suspended from an overhead support, and having oppositely disposed seats; a treadle for moving said swing, said treadle having one end secured to the floor of the swing and the other end projecting outside of the swing; a 45 chain attached to the outer end of said treadle and having the other end attached to said support; and a slide mounted over the outer end of said treadle adapted to be 50 opened and closed by the movement thereof, and remain closed when said treadle is at rest, substantially as described.

7. In an insect-proof swing suspended from an overhead support, and having oppositely disposed seats; a treadle for moving 55 said swing, said treadle having one end secured to the floor of the swing and the other end projecting outside of the swing; a chain attached to the outer end of said 60 treadle and having the other end attached to said support; a slide mounted over the outer end of said treadle adapted to be opened and closed by the movement thereof, and remain closed when said treadle is at rest; a ground- 65 engaging member on said swing for locking the same against swinging motion; a lever-operating means for raising and lowering said ground-engaging member relatively to 70 said swing; and means for locking said member in its raised or lowered position, substantially as described.

In testimony whereof I have signed my name to this specification in the presence of two subscribing witnesses.

BERNHARD H. WITTE.
